DESIGN FOR A DOILY OR SIMILAR ARTICLE

John S. Madsen, New York, N. Y.

Application April 21, 1939, Serial No. 84,470

Term of patent 3½ years

To all whom it may concern:

Be it known that I, John S. Madsen, a citizen of the United States of America, residing in the city of New York, county of New York, and State of New York, have invented a new, original, and ornamental Design for a Doily or Similar Article, of which the following is a specification, reference being had to the accompanying drawing, forming part thereof.

The figure on the drawing is a plan view of a doily or similar article showing my new design.

I claim:

The ornamental design for a doily or similar article, substantially as shown.

JOHN S. MADSEN.
